Drawer 2nd & Major

UNITED STATES PATENT OFFICE.

ERNEST WILLOUGHBY PETTER, OF LONDON, ENGLAND.

MEANS FOR CONTROLLING THE SUPPLY OF LIQUID FUEL TO INTERNAL-COMBUSTION ENGINES.

1,252,166.

Specification of Letters Patent.

Patented Jan. 1, 1918.

Application filed May 3, 1916. Serial No. 85,032.

To all whom it may concern:

Be it known that I, ERNEST WILLOUGHBY PETTER, residing at 73 Queen Victoria street, London, England, subject of the King of Great Britain and Ireland, have invented certain new and useful Improvements in Means for Controlling the Supply of Liquid Fuel to Internal-Combustion Engines, of which the following is a specification.

10 This invention relates to internal combustion engines using liquid fuel, and provides a means of governing the amount of fuel delivered to the engine, and a means for adjusting the moment of injection of the 15 fuel so as to make it earlier or later as required to suit the working conditions of the engine.

In order to obtain this result a shaft governor of the usual type is fitted to the engine crank shaft or to some other shaft geared thereto. The governor consists of a member or casing upon which is formed an eccentric. On said eccentric is mounted a second or outer eccentric. On said outer 25 eccentric is mounted a strap and connecting rod which operate the fuel injection pump. This casing is carried upon a casting which I will call the carrier, the said carrier being keyed to the engine crank shaft. The aforesaid casing is provided with a pair of symmetrically arranged weights, each of which is pivoted to the casing at one end, being free to move around this pivot in a plane vertical to the shaft. The said outer eccentric 30 is fitted to the casing in such a way that the movement of the weights under the action of centrifugal force serves to increase or decrease the eccentricity of the said outer eccentric and by means of this variation in the eccentricity, the amount of fuel delivered to the engine is governed according to the working load.

The casing is fixed to the carrier by means of one or more studs screwed into the casing 45 and passing through concentric slots in the carrier, these slots being of any desired length. By rotating the casing to any desired position and locking it by tightening the nuts on the studs the inner eccentric on the shaft is rotated so as to advance or retard the moment of fuel injection.

Figure 1 is an elevation of one form of apparatus made in accordance with this invention;

Fig. 2 is a section;

Fig. 3 is an elevation;

Fig. 4 a section showing the means of adjusting the position of the inner eccentric in relation to the casing and shaft.

Upon the shaft *a* is fitted a carrier comprising a pulley *b* having a sleeve *c*, the carrier being provided with concentric slots *d d*. On the sleeve *c* is disposed a casing *e* adapted to be adjusted angularly on the carrier and to be secured in position by the 60 studs and nuts *f f*. Upon the casing *e* is formed an eccentric *g* which bears on the shaft *a*. On this eccentric is disposed the pump eccentric *h*. The eccentric *h* is provided with lugs *j j*. On the casing *e* are 65 mounted weights *k k* pivoted at *m m*. Links *n n* connect the weights *k k* to the lugs *j j*. The weights *k k* are held toward the shaft *a* by means of springs *o o* which are attached to the casing at *p p* and to the weights at *q*. 70 Upon the eccentric *h* is disposed the strap *r* to which the pump connecting rod *s* is attached.

In operation as the speed increases the weights *k k* fly out and pull the eccentric *h* 80 around eccentric *g* on the shaft *a* whereby the eccentricity is reduced and consequently the throw of the pump and the amount of fuel supplied to the combustion chamber. In order to alter the moment when the fuel 85 is injected the casing *e* and with it the inner eccentric *g* is moved in relation to the carrier which is keyed to the shaft.

What I claim and desire to secure by Letters Patent is:—

90 Means for delivering fuel to internal combustion engines and for regulating the amount of fuel delivered comprising a reciprocating pump, means for actuating said pump comprising a rotary shaft, a carrier keyed to the said shaft, a member adjustably mounted on said carrier, an eccentric on said member, means for adjusting said inner eccentric angularly in relation to the carrier for the purpose of adjusting the 95 moment of injection of the fuel, means for fixing the said member to the carrier, an outer eccentric mounted on the eccentric disposed on the said member, centrifugal means for moving the outer eccentric angularly in 100 relation to the said member and to the eccentric thereon, a strap on said outer eccentric, and means for connecting said strap

- to the portion of said reciprocating pump,
said centrifugal means comprising weights
pivotally mounted on said member and free
to move in a plane vertical to the shaft, lugs
5 on said outer eccentric, links connecting said
lugs to said weights and springs adapted to
keep the weight toward the shaft.

In witness whereof, I have hereunto signed
my name in the presence of two subscribing
witnesses.

ERNEST WILLOUGHBY PETTER.
